SELF-LOADING DEVICE FOR SHAKER CONVEYORS

Ernst R. Bergmann, Chicago, Ill., assignor to
 Goodman Manufacturing Company, Chicago,
 Ill., a corporation of Illinois

Application January 12, 1946, Serial No. 640,875

8 Claims. (Cl. 198—14)

1

This invention relates to improvements in self-loading devices for shaker conveyors of the type utilized for picking up coal, rock or the like from the ground in mines.

The principal objects of my invention are to provide a novel and simplified form of self-loading device for a shaker conveyor, of the type having draft devices for swinging the pick-up end of the conveyor laterally along the ground and having a frame extending along the pick-up end of the conveyor and forming a non-reciprocating reaction member for the draft devices, which frame is so arranged as to maintain the draft devices close to the ground by the pull of said draft devices on said frame.

The device of my present invention is disclosed but not claimed in an application Serial No. 620,362, filed by William W. Sloane on October 4, 1945, relating to the feeding mechanism for extensibly and retractibly moving the extensible trough of the conveyor.

My invention may be more clearly understood with reference to the accompanying drawings wherein:

Figure 1 is a plan view of a loading device constructed in accordance with my invention;

Figure 2 is an enlarged plan view of the inby or forward end of the loading device with certain parts broken away and certain other parts shown in substantially horizontal section;

Figure 3 is an enlarged fragmentary view in side elevation of the forward or inby part of the loading device with certain parts shown in substantially longitudinal section in order to show certain details of my invention which are not shown in Figure 2;

Figure 4 is a transverse sectional view taken substantially along line 4—4 of Figure 2;

Figure 5 is an enlarged plan view of the rear part of the loading device with certain parts broken away and certain other parts shown in substantially horizontal section, in order to show certain details of the swivel for controlling lateral movement of the inby end of the loading device;

Figure 6 is a view in side elevation of the swivel shown in Figure 5;

Figure 7 is a sectional view taken substantially along line 7—7 of Figure 2;

Figure 8 is a sectional view taken substantially along line 8—8 of Figure 5;

Figure 9 is a sectional view taken substantially along line 9—9 of Figure 5;

Figure 10 is a sectional view taken substantially along line 10—10 of Figure 5; and

Figure 11 is a sectional view taken substantially along line 11—11 of Figure 5.

In the drawings, the embodiment of my invention illustrated therein includes generally an extensible trough 10 having a shovel 11 on its forward end, which slidably supports the forward end of said extensible trough on the ground and

2

is adapted to pick up loose material from the ground. The rear end of said extensible trough is slidably supported above the ground on a ground-engaging shoe 12 by means of a pair of laterally spaced supporting legs 14, 14 transversely pivoted to said shoe and extending upwardly therefrom along the outer sides of a reciprocating trough 15, within which said extensible trough is nested. Said supporting legs are suitably secured at their upper ends to the rear end portions of bearing plates 17, 17, extending along the upper outer sides of said reciprocating trough. Said bearing plates are adapted to be engaged by friction grip blocks 19, 19 of a feeding mechanism generally indicated by reference character 20 for extensibly or retractibly moving said extensible trough with respect to said reciprocating trough by the action of the conveyor, in a manner well known to those skilled in the art.

20 The reciprocating trough 15 is connected to and reciprocably driven from the shaker conveyor trough line through an articulated trough connection or swivel 21, which is so arranged as to form a means for controlling lateral movement of said reciprocating and extensible troughs, and to permit the continuous flow of material along said reciprocating trough and swivel to the outby end of the trough line, when said reciprocating and extensible troughs are in various positions of lateral displacement with respect to the trough line. Said swivel is clearly shown and described in application Serial No. 637,645, filed by William W. Sloane on December 28, 1945, so will only herein be shown and described in so far as is necessary to make my present invention clearly understandable.

25 The bearing plates 17, 17 also form a supporting means for the forward end of the reciprocating trough 15 on rollers 22, 22 (see Figure 3). Said rollers are mounted on opposite upright side walls 23, 23 of a supporting frame 24, secured to and extending across the bottom of and upwardly along opposite sides of the forward end of said reciprocating trough beyond the upper limits thereof and in advance of the forward end thereof.

30 The supporting frame 24 has the feeding mechanism 20 pivotally connected thereto and extending in advance thereof. Said feeding mechanism and its connection to the supporting frame 24 are clearly shown and described in the aforementioned application Serial No. 620,362, filed by William W. Sloane on October 4, 1945, and 35 are no part of my present invention so will not herein be shown or described in detail.

35 The reciprocating trough 15 is suitably connected at its rear end to a connecting trough 29 of the swivel 21. Said swivel includes a relatively short intermediate trough 31 having a flared

60

curved rear end of the connecting trough 29 nested therein. The rear end of said intermediate trough is of a flared curved formation and is nested within a correspondingly curved flared receiving end of a connecting trough 34. Said connecting trough is secured to the forward end of a trough 35 forming the inby end of the shaker conveyor trough line. Pivotal vertical bearing members 36 and 37 are provided to pivotally connect said swiveled intermediate trough to said troughs 29 and 34.

The bearing member 36 and connecting trough 29 are mounted on a support frame 39 which extends rearwardly therefrom and is reciprocably supported adjacent its rear end on guide rollers 40, 40. Said rollers are mounted on opposite sides of a control frame 41 which is pivotally mounted on a bearing boss 43, projecting upwardly from a floating plate 44 of the swivel 21.

The floating plate 44 forms a support for the operative parts of the swivel and is pivotally mounted adjacent one of its sides on a stationary base 45 on a longitudinal shaft 46, and is restrained from upward movement with respect to said base by springs 49, 49 having engagement with the side of said plate opposite from said shaft. Said base is adapted to be held in position on the ground by suitable jacks (not shown) engaging opposite sides thereof and interposed between said base and the mine roof.

Two winding drums 67, 69 are mounted on a base 69, which may be detachably secured to the base 45. Flexible draft devices such as cables 70, 71 are adapted to be wound on or payed off of said winding drums. A motor 72 mounted on said base, is provided to drive said winding drums through a suitable gearing (not shown) in such a manner that one winding drum will wind in one draft device while the other winding drum pays out its draft device (see Figure 1). The drive from said motor to said winding drums may be of a type similar to that shown and described in Patent No. 2,272,049, which issued to Loy D. Hagenbook on February 3, 1942, and is no part of my present invention so will not herein be shown or described.

The base 69 is adapted to rest on the ground and is detachably connected at its forward end to the stationary base 45 by means of a forwardly projecting connecting member 73 interleaving a connecting member 74 and pivotally connected thereto by means of a pivotal pin 75. A connecting arm 76 extending diagonally beneath the trough line in a substantially horizontal plane, is provided to connect the inner side of said base 69 with the rear right-hand corner of the base 45, and is connected to said bases at its opposite ends by vertically disposed pivotal pins 77, 77.

The reaction and guide means for the flexible draft devices 70 and 71, for causing said draft devices to laterally move the troughs 10 and 15 about the axis of the bearing boss 43 includes a non-reciprocating frame 81 mounted beneath and extending along the reciprocating trough 15. Said frame is secured at its rear end to the forward ends of laterally spaced forwardly projecting arm portions 83, 83 of the control frame 41 by means of nuts and bolts 84, 84 (see Figure 5). From said arms said frame extends forwardly beneath the reciprocating trough 15 to a point adjacent the forward end thereof. Two laterally spaced longitudinally extending bearing members 85, 85 are mounted on and extend along opposite sides of the forward end of said frame. Said bearing members have concave outwardly facing bearing

surfaces which are adapted to be engaged by inwardly facing bearing surfaces of bearing members 86, 86 (see Figures 2 and 4). Said bearing members 86, 86 are each pivotally mounted on the insides of depending sides 87, 87 of the support frame 24 on shafts 88, 88 extending inwardly of said bearing members and pivotally mounted on bearings 89, 89, secured to and extending inwardly of said depending sides.

A connecting ear 90 projects forwardly from each side of the forward end of the frame 81. Each of said ears extends between the furcations of a short upright bifurcated connecting arm 91. Said upright arms project upwardly from the rear end of a floating frame 93 and are pivotally connected to said ears by means of pivotal pins 94, 94 disposed above the top of said floating frame. Said floating frame extends in advance of said frame 81 into slidably engagement with the ground and forms a floating forward portion of said frame which is adapted to be held in floating engagement with the ground by lateral pull of the flexible feeding members 70, 71, to maintain said flexible feeding members close to the ground, when trained laterally from said frame.

A roller 95 for the cables 70, 71 is journaled between the upright arms 91, 91 on a transverse shaft 96 which is secured at its ends to the inside furcations of said upright arms. The upper surface of said roller substantially intersects the pivotal axis of the pins 94, 94, and is so positioned that when said flexible feeding members are trained laterally around sheaves 97, 97 at the forward end of said frame and are secured adjacent the ground to fixed abutments remote from said frame at their free ends, said flexible feeding members will maintain the forward end of said frame in floating engagement with the ground, which will assure that said flexible feeding members will be trained close to the ground and will be out of the way of the men moving back and forth towards and from the working face.

The guide sheaves 97, 97 are mounted at the forward end of the floating frame 93 on vertical pins 98, 98 mounted in the bottom of said frame and extending upwardly therefrom. Cable retaining covers 99, 99 are longitudinally pivoted adjacent the central part of said guide frame on pivotal pins 100, 100 (see Figures 2, 3 and 7) and cover the tops of said guide sheaves. The cables 70, 71 are trained rearwardly from said sheaves over the roller 95 and rearwardly along the frame 81 between the sides thereof, to and around guide sheaves 101, 101 mounted on vertical pins 102, 102, adjacent the rear end of said frame. From thence said cables extend angularly outwardly and are trained between guide sheaves 103, 103, 104, 104. Said guide sheaves are coaxially mounted on parallel laterally spaced vertical shafts 105 and 106, respectively, which shafts are mounted in a housing 107, herein shown as being formed integrally with and extending outwardly from the left-hand arm portion 83 of the control frame 41. From thence said cables are trained along the outer sides of guide sheaves 103, 103 coaxially mounted on a vertical shaft 109 and housed in a sheave housing 111 secured to the left-hand forward corner of the floating plate 44. The cable 70 extends from its associated sheave 103 rearwardly along the outer side of a guide sheave 112 and the inner side of a guide sheave 113 to the winding drum 67, on which it is wound. The cable 71 extends rear-

wardly from its associated guide sheave 109 along the underside of a guide sheave 115 to and is wound on the winding drum 68.

When power is transmitted to the winding drums 67 and 68, from the motor 72, to wind cable on one winding drum and pay cable off the other winding drum, and when the free ends of the cables 70 and 71 are attached adjacent the ground to fixed abutments, such as jacks (not shown), interposed between the mine roof and the mine bottom, the pull on one cable will move the extensible and reciprocating troughs about the axis of the bearing boss 43, lateral movement of which is controlled by the control frame 41, to position the shovel 11 to pick up loose material from either side of the shaker conveyor trough line. During this lateral movement of said extensible trough and shovel, the reaction on the floating portion of the guide 81 caused by lateral pull of the cables 70 and 71 connected to their associated jacks adjacent the ground, will hold said floating portion of said frame in floating engagement with the ground, and will assure that the cables 70 and 71 are trained from their respective sheaves 96, 96 along the ground out of the way of the men working adjacent said extensible trough and coming to and from the working face.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a self-loading device for shaker conveyors and in combination with a shaker conveyor trough line, a reciprocating trough connected to the inby end of said trough line for lateral movement with respect thereto, an extensible trough adapted to pick up loose material from the ground and mounted for extensible or retractible movement, and means for laterally swinging said extensible and reciprocating troughs along the ground including a non-reciprocating frame extending along said reciprocating and extensible troughs and having engagement with opposite sides of said reciprocating trough, winding means having two flexible feeding members extending therefrom and along said frame and adapted to be trained in opposite directions from the forward end of said frame to abutments remote from said troughs, for moving said troughs in one direction or another upon winding in of either one of said flexible feeding members, said frame having a transversely pivoted forward portion having floating engagement with the ground adjacent its forward end and adapted to train said flexible feeding members laterally from said frame adjacent the ground, and said flexible feeding members being trained laterally from said floating forward portion of said frame and being arranged to maintain the forward end of said floating portion of said frame in floating engagement with the ground when either one of said flexible feeding members is wound in by said winding means.

2. In a self-loading device for shaker conveyors and in combination with a shaker conveyor trough line, a reciprocating trough connected to the inby end of said trough line for lateral movement with respect thereto, an extensible

trough adapted to pick up loose material from the ground and mounted for extensible or retractible movement with respect to said reciprocating trough, and means for laterally moving said extensible and reciprocating troughs along the ground including a non-reciprocating frame extending along said reciprocating and extensible troughs and having engagement with opposite sides of said reciprocating trough, winding means having two flexible feeding members extending therefrom and along said frame and adapted to be trained in opposite directions from the forward end of said frame to abutments remote from said troughs, for moving said troughs in one direction or another upon winding in of either one of said flexible feeding members, and said frame having a forward portion having floating engagement with the ground at its forward end and having a pair of sheaves mounted adjacent its forward end for rotation about parallel spaced axes perpendicular to the top surface of said floating forward portion of said frame, for training said flexible feeding members laterally from the forward end of said floating portion of said frame and maintaining said flexible feeding members close to the ground, said sheaves being disposed in such a plane that the reaction against said sheaves caused by pull of said flexible feeding members will hold the forward end of said floating portion of said frame in engagement with the ground.

3. In a self-loading device for shaker conveyors and in combination with a shaker conveyor trough line, a reciprocating trough connected to the inby end of said trough line for lateral swinging movement with respect thereto, an extensible trough adapted to pick up loose material from the ground and mounted for extensible or retractible movement with respect to said reciprocating trough, and means for laterally swinging said extensible and reciprocating troughs along the ground including a non-reciprocating frame engaging opposite sides of said reciprocating trough and extending beneath said reciprocating and extensible troughs, winding means having two flexible feeding members extending therefrom and along said frame and adapted to be trained in opposite directions from the forward end of said frame and to be secured adjacent the ground to fixed abutments remote from said troughs, for swinging said troughs in one direction or another, and said frame having a floating forward portion pivotally mounted for movement about a transverse axis so as to have floating engagement with the ground at its forward end and having a pair of sheaves mounted at the forward end of said floating portion of said frame for rotation about axes perpendicular to the top surface of said floating forward portion of said frame, for training said flexible feeding members along the ground laterally from the forward end of said floating portion of said frame, the top surface of said floating portion of said frame being normally spaced beneath the axis of transverse pivotal movement thereof, and said flexible feeding members passing over said floating portion of said frame, adjacent the pivotal axis thereof in a plane substantially intersecting the pivotal axis of said floating portion of said frame, and passing around said sheaves in a plane which is normally disposed beneath the pivotal axis of said frame, so the reaction caused by lateral pull of either of said flexible feeding members will hold said floating forward portion

of said frame in floating engagement with the ground.

4. In a self-loading device for shaker conveyors and in combination with a shaker conveyor trough line, a reciprocating trough connected to the inby end of said trough line for lateral swinging movement with respect thereto, an extensible trough adapted to pick up loose material from the ground and mounted for extensible or retractile movement with respect to said reciprocating trough, and means for laterally swinging said extensible and reciprocating troughs along the ground including a non-reciprocating frame engaging opposite sides of said reciprocating trough and extending beneath said reciprocating and extensible troughs, winding means having two flexible feeding members extending therefrom and along said frame and adapted to be trained in opposite directions from the forward end of said frame and to be secured adjacent the ground to fixed abutments remote from said troughs, for swinging said troughs in one direction or another, and said frame having a floating forward portion adapted to have floating engagement with the ground, said floating forward portion of said frame being transversely pivoted adjacent its opposite sides for vertical movement about its rear end, and a roller adapted to be engaged by said flexible feeding members in a plane substantially intersecting the axis of pivotal movement of said frame, to form a reaction member for said flexible feeding members during lateral pull thereof and cause said flexible feeding members to hold the forward end of said floating portion of said frame in floating engagement with the ground when trained laterally from the forward end of said frame and secured adjacent the ground to fixed abutments at their free ends.

5. In a self-loading device for shaker conveyors and in combination with a shaker conveyor trough line, a reciprocating trough connected to the inby end of said trough line for lateral swinging movement with respect thereto, an extensible trough adapted to pick up loose material from the ground and mounted for extensible or retractile movement with respect to said reciprocating trough, and means for laterally swinging said extensible and reciprocating troughs and extending beneath said reciprocating and extensible troughs, winding means having two flexible feeding members extending therefrom and along said frame and adapted to be trained in opposite directions from the forward end of said frame and to be secured adjacent the ground to fixed abutments remote from said troughs, for swinging said troughs in one direction or another, and said frame having a floating forward portion adapted to have floating engagement with the ground, said floating forward portion of said frame being transversely pivoted adjacent its opposite sides for pivotal movement in a vertical direction about its rear end, two sheaves mounted at the forward end of said frame for rotation about axes substantially perpendicular to the top surface of said floating frame, and a roller for said flexible feeding members at the rear end of said floating frame, said roller having an engaging surface adapted to be engaged by said flexible feeding members in planes substantially intersecting the pivotal axis of said floating portion of said frame, and said guide sheaves being normally disposed beneath the pivotal axis of said floating portion of said frame so the lateral pull of either of said flexible feeding members

when secured at their free ends adjacent the ground will tend to hold the floating forward portion of said frame in engagement with the ground.

6. In a self-loading device for shaker conveyors, 5 an articulated trough connection connected to the inby end of a conveyor trough line and including a stationary base having a plurality of articulated troughs mounted thereon for movement about a plurality of parallel spaced vertical axes, said 10 articulated troughs including a laterally swingable connecting trough spaced forwardly of said base and having a forwardly extending reciprocating trough connected to and reciprocably driven therefrom, an extensible trough mounted 15 for extensible and retractile movement with respect to said reciprocating trough and having a ground engaging shovel projecting from its forward end and forming a support for the forward end of said trough on the ground, and means for 20 feeding said troughs laterally to position said shovel to pick up loose material from either side of said articulated trough connection including a non-reciprocating frame extending beneath and within the lateral limits of said reciprocating and 25 extensible troughs and connected at its rear end to said swivel for lateral movement about its rear end in a controlled path, and having slidale engagement adjacent its forward end with opposite sides of said reciprocating trough, a pair of flexible 30 feeding members extending from said base along said frame within the lateral limits of said frame and adapted to be trained laterally from said frame and be secured adjacent the ground to fixed abutments remote from said frame, and 35 said frame having a transversely pivoted forward end portion having floating engagement with the ground at its forward end and having guide sheaves mounted adjacent its forward end, for training said flexible feeding members laterally 40 therefrom, said sheaves being so arranged with respect to the transverse pivotal axis of said floating forward portion of said frame as to maintain said flexible feeding members close to the ground and to hold the forward end of said frame 45 in floating engagement with the ground by lateral pull of said flexible feeding members on said sheaves.

7. In a self-loading device for shaker conveyors, an articulated trough connection connected to the inby end of a conveyor trough line and including a stationary base having a plurality of articulated troughs mounted thereon for movement about a plurality of parallel spaced vertical axes, said articulated troughs including 55 a laterally swingable connecting trough spaced forwardly of said base and having a forwardly extending reciprocating trough connected to and reciprocably driven therefrom, an extensible trough mounted for extensible and retractile movement with respect to said reciprocating trough and having a ground engaging shovel projecting from its forward end and forming a support for the forward end of said trough on the ground, and means for feeding said troughs laterally to position said shovel to pick up loose material from either side of said articulated trough connection including a non-reciprocating frame extending beneath and within the lateral limits of said reciprocating and extensible troughs and connected at its rear end to said swivel for lateral movement about its rear end in a controlled path, and having slidale engagement adjacent its forward end with opposite sides of said reciprocating trough, a pair of flexible 70 feeding members extending from said base 75

along said frame within the lateral limits of said frame and adapted to be trained laterally from said frame and be secured adjacent the ground to fixed abutments remote from said frame, and said frame having a transversely pivoted forward end portion having floating engagement with the ground at its forward end, and a roller adjacent the pivotal axis of said floating frame adapted to be engaged by said flexible feeding members, the surface of said roller over which said flexible feeding members pass being substantially in alignment with the pivotal axis of said floating frame, and guide sheaves adjacent opposite sides of the forward end of said floating frame for training said flexible feeding members laterally therefrom, said guide sheaves being disposed closely adjacent the ground so as to maintain the forward end of said floating frame in floating engagement with the ground and to maintain said laterally projecting portions of said flexible feeding members adjacent the ground during operation of said loading device.

8. In a self-loading device for shaker conveyors and in combination with a shaker conveyor trough line, a reciprocating trough connected to the inby end of said trough line for lateral movement with respect thereto, an extensible trough mounted for extensible or retractible movement with respect to said reciprocating trough, and means for moving said extensible and reciprocating troughs laterally along the ground including a non-reciprocating

frame extending along said reciprocating trough and having engagement therewith for laterally moving said reciprocating and extensible troughs upon lateral movement of said frame, a flexible feeding member extending along said frame and adapted to be trained laterally from the forward end of said frame to a fixed abutment remote from said trough, for laterally moving said frame and troughs upon the winding in of said flexible feeding member, said frame having a forward end portion extending forwardly therefrom and pivotally connected thereto for movement about a transverse axis so as to have floating engagement with the ground adjacent its forward end, and guide means for said flexible feeding member mounted adjacent the forward end of said floating forward end portion of said frame, for training said flexible feeding member laterally from said frame, said guide means being so located with respect to the pivotal axis of said floating forward end portion of said frame that the lateral pull of said flexible feeding member on said guide means, when said flexible feeding member is secured at its free end to a fixed abutment adjacent the ground, will maintain said floating forward end of said frame in floating engagement with the ground, and will maintain said flexible feeding member adjacent the ground during lateral movement of said frame along the ground.

ERNST R. BERGMANN.
